MULTIPLE LIQUID PROCESSING CONTAINER

Frank Palik, Kensington, Md.

Application April 18, 1947, Serial No. 742,484

2 Claims. (Cl. 137—21)

1

This invention relates to liquid contact apparatus and more particularly to novel apparatus for treating soil material with a processing liquid. An example of such an apparatus is one adapted to process tissue specimens for microscopic examination.

The conventional manual steps in preparing specimens for microscopic examination in a pathological laboratory are to fix and dehydrate them by transferring them by hand, in the proper sequence, from one container of a desired solution to others containing other solutions. This lends itself to human errors in timing the various steps; there is always the possibility of an error in the sequence of steps and a laboratory technician must be in attendance constantly during processing.

An important object of the invention is to provide such an apparatus wherein, aside from the introduction of the material to be processed and its removal after processing, the various steps are carried on automatically, whereby the human error factor is eliminated.

Where manual or automatic processing is carried on by mechanical removal of the specimens or material from a solution in one container to a solution in another container, dripping of solution occurs during such transfers.

Another important object is to provide an automatic processing apparatus wherein but one container is employed which, in turn, contains one liquid after another, so that the material remains in the same container from the start of processing until the conclusion thereof. That is, the material, upon introduction into the container, may be treated with a certain solution automatically introduced thereto, the solution automatically drained therefrom after a predetermined period, the material automatically washed (if desired), the washing fluid automatically removed, another solution automatically introduced, the material treated therewith for a predetermined period (which may be greater or less than the time of the previously-mentioned period), this solution automatically drained, and so on. The material, consequently, does not leave the container for the material and solutions during the entire processing.

Obviously, in removing material from a bath in one container and introducing it to a bath within another container, even if done automatically, there is the temperature factor to be considered. It may be undesirable to expose the material to an abrupt change in temperature (as that of a solution from which the material was

2

removed and the temperature of the outside air encountered during transfer from one container to another).

Still another important object is to provide an apparatus for automatically processing material wherein the material need not be exposed to the air outside the container during the entire processing.

Unless cumbersome closure operators are employed to automatically open and close one container after another for the introduction and removal of material, it is obvious that, unless the outside air is of substantially the same temperatures as that of the various solutions, during the processing cycle, each solution will gradually vary in temperature during the processing step in which it is employed.

A further important object of the invention is to prevent the exposure of the various solutions to the outside air during the entire automatic processing of the material.

Where a pivoted arm is provided, carrying a suitable vessel at its free end, which vessel is adapted, upon step-by-step rotation of the arm, to dip into various containers arranged in a circle, it is obvious that considerable floor space is necessary.

An object of this invention is to provide an apparatus as described which occupies but little floor space.

Other objects and advantages of the invention will be apparent during the following detailed description of the invention, taken in connection with the accompanying drawing, forming a part of this specification, and in which drawing:

35 Figure 1 is an elevation of the novel processing apparatus.

40 Figure 2 is a vertical section of the upper portion thereof, substantially on the line 2—2 of Figure 1.

45 Figures 3 and 4 are horizontal sections upon their respective lines in Figure 1.

In the drawing wherein for the purpose of illustration is shown a preferred embodiment of the invention and wherein similar reference characters designate corresponding parts throughout the several views, the letter A designates the apparatus as a whole, including an outer container B, inner container C, inlet conduits D, 50 outlet conduits E, means F for rotating one of said containers and conventional means G for timing the means F.

The outer container B is shown as a double-walled cylinder, open at its upper and lower ends, the upper open end constituting a mouth 5 and

the inner surface 6 of the cylinder providing a smooth surface for contact with the outer surface of the inner container C. The space 7 between the inner and outer walls of the container B constitutes a space for insulating purposes or to contain a heating or a cooling means (not shown). As may be seen in Figure 4, the container B may be provided with, preferably, a plurality of spaced-apart bores 8 at its lower end portion 9, for portions of the inlet conduits D and outlet conduits E.

Within the container B is the inner container C which may also be a cylinder open at its upper end, providing a mouth 10, and closed at its lower end by a bottom wall 11. The outer surface 12 of the container C is constructed and arranged for an intimate but slideable fit with the surface 6 preferably throughout the length of the surface 6, whereby the wall of the container B adds to the thickness of the wall of the apparatus A and further insulates the contents of the container C.

As shown in Figure 4, the container C may be provided, at its lower end, just above the wall 11 with an opening 13, constructed and arranged so that, as one or the other container rotates, this opening 13 will align with one after another of the bores 8. A removable closure 14 may be provided for the container C.

The inlet conduits D may be of the same number as there are possible liquids to be introduced into the container C, and they may be connected with the container B in any approved way. For example, the bores 8 may be screw-threaded as shown and the ends of the conduits D may be exteriorly screw threaded to cooperate with the screw threads of the bores 8. These conduits lead, of course, from various reservoirs (not shown) of solutions (or reservoirs of solutions and reservoirs of water).

Alternating with the conduits D are the conduits E which may also be of the same number as there are possible liquids to be discharged from the container C, and they may be connected with the container B in the same way as are the conduits D. They lead to suitable liquid discharge means.

The conduits D and E may provide the support means for the container B.

In the example shown, the container C rotates within the container B. Rotation may be provided by the means F which includes a shaft 15 secured to the vertical axial center of the bottom wall 11, depends therefrom and carries means, such as the bevel gear 16 meshing with means, such as the bevel gear 17, carried by the shaft 18 of an electric motor 19.

As is well known in the art, a conventional timer means G may be provided and operatively connected with the means F.

In the operation of the novel apparatus A, after the material has been inserted into the container C (for example, the material may be within a suitable container having foraminous walls) and its opening 13 aligned with the proper bore 8 with which is connected the conduit D leading to the source of the first liquid to be employed, the closure 14 may be replaced, the timer G set into operation and the following sequence of steps ensue: the first liquid will flow into the container C for treating the material therein. After a predetermined timing to permit enough of this first liquid to enter the container C, the timer G will set into operation the means F which will rotate the container C sufficiently to close the

bore 8 and flow of liquid will cease, the timer G will then stop the operation of the means F or permit the container C to rotate until the opening 13 therein aligns with the bore 8 next adjacent the bore 8 mentioned. Since this last bore 8 is connected with a discharge or outlet conduit E, and the liquid will drain from the container C whereupon the timer G will again set in motion the means F and rotation of the container C will bring the next adjacent bore 8 into communication with the opening 13, and, either a second treating solution or wash water (as determined) will flow into the container C from the conduit D connected with that bore 8. With this explanation, it will be obvious that any reasonable number of alternate treating and draining steps may be carried on. Of course, it is now obvious that the timer may be employed simply to start and stop the means F since a slow rotation of the container C with the bores 8 properly spaced, will permit entry of the first treating liquid, stopping of its flow to the container C, a period during which the treating liquid contacts the material, the discharge of the treating liquid, a period during which the material is not treated, the entry of another liquid, the stopping of its flow into the container C, a period in which this second liquid contacts the material, the draining of this second liquid, and so on. In either case, the material is not removed from the one container during the entire processing period, the outside air need not reach it (other than to prevent a vacuum or pressure within the emptying or filling container C), and the various steps are positive and fixed against the errors due to manual carrying out of the process.

The apparatus described herein, while designed primarily for use in a pathological laboratory, is of much broader scope and envisages other industrial applications such as the dyeing of fabrics and materials, processing of photographic film, etc.

Various changes may be made to the form of the invention herein shown and described without departing from the spirit of the invention or scope of the claims.

What is claimed is:

1. A multi-stage processing apparatus for treating material in turn with a plurality of liquids, including an outer container having a side wall provided with a substantially cylindrical inner surface, an upwardly-opening mouth opening to said surface, and a plurality of spaced-apart bores extending from the exterior to the interior of said container; an inner container including a bottom wall and side wall secured to the bottom wall defining a material-receiving and treating chamber, said last-named side wall having a substantially cylindrical outer surface in sliding contact with said inner surface, an upwardly-opening mouth to said chamber, said mouths being axially aligned, and a single opening in the lower portion only of said last-named side wall constructed and arranged, upon rotation of one of said containers, to align with one and then another of said bores, said opening extending from said chamber to said outer surface; means to rotate one of said containers; separate means connected with each of some of said bores to conduct a separate liquid to each of said some of said bores; and separate means connected with each of the other of said bores to conduct a separate liquid from each of said other of said bores.

2. A multi-stage processing apparatus according to claim 1 in which the upper edges of said side walls at said mouths are in substantially the same horizontal plane, and said apparatus includes a removable closure covering the upper edge of said last-named side wall.
